(57) **CLAIM**

An ornamental design for a memo paper dispenser, as shown and described.

DESCRIPTION

FIG. 1 is a front view of the memo paper dispenser showing my new design;

FIG. 2 is a rear view thereof;

FIG. 3 is a left side view thereof;

FIG. 4 is a right side view thereof;

FIG. 5 is a top plan view thereof;

FIG. 6 is a bottom plan view thereof; and,

FIG. 7 is a perspective view thereof.

The broken lines in FIG. 6 are included for the purpose of showing features on the memo paper dispenser that form no part of the claimed design.
